UNITED STATES PATENT OFFICE.

CHARLES A. LINDBERG, OF STURGIS, MICHIGAN, ASSIGNOR TO STURGIS STEEL GO-CART CO., OF STURGIS, MICHIGAN, A CORPORATION OF MICHIGAN.

WHEEL-RETAINER.

1,345,545.

Specification of Letters Patent.

Patented July 6, 1920.

Application filed August 22, 1919. Serial No. 319,236.

To all whom it may concern:

Be it known that I, CHARLES A. LINDBERG, citizen of the United States, residing at Sturgis, county of St. Joseph, State of Michigan, have invented certain new and useful Improvements in Wheel-Retainers, of which the following is a specification.

This invention relates to improvements in wheel retainers.

10 The main objects of this invention are to provide an improved wheel retainer which is well adapted for use in light vehicles such as children's carriages, which is concealed from view and at the same time readily adjusted to secure or release the wheel.

Further objects, and objects relating to structural details, will definitely appear from the detailed description to follow.

I accomplish the objects of my invention 20 by the devices and means described in the following specification. The invention is clearly defined and pointed out in the claims.

A structure which is a preferred embodiment of my invention is clearly illustrated 25 in the accompanying drawing forming a part of this specification, in which:

Figure I is a detail elevation of a structure embodying the features of my invention, only such parts being illustrated as 30 seem advisable to show an application of my improvements.

Fig. II is a detail vertical section on a line corresponding to line 2—2 of Fig. III.

Fig. III is a detail horizontal section on 35 a line corresponding to line 3—3 of Fig. I.

Fig. IV is a detail vertical section corresponding to Fig. II, with the retaining dog in its retracted position.

In the drawing similar reference characters refer to similar parts throughout the 40 several views, and the sectional views are taken looking in the direction of the little arrows at the end of the section lines.

Referring to the drawing, 1 represents the 45 axle, 2 a wheel thereon and 3 a side member of the running gear frame of a child's carriage embodying the features of my invention. The hub 4 of the wheel is provided with ball bearings 5 and a cap 6 closing the outer end of the hub. The axle is hollow, it being illustrated formed from a piece of sheet steel. The axle is provided with a thrust collar 7 for the inner end of the hub.

The wheel retaining dog 8 is formed of a 55 rod or bar, and has a laterally turned en-

gaging portion 9 at its outer end adapted to be projected through the hole 11 in the axle, to project at the outer side of the outer bearing 5, and thereby retain the wheel—see Fig. II.

The retaining dog is provided with an offset 60 12 at its inner end, the offset being formed so that the dog also engages the axle at 13 and 14, thereby supporting the dog in an outwardly inclined position with its engaging portion 9 normally retracted.

To actuate or project the retaining dog, 1 provide a reciprocating actuating member 15 having a laterally offset curved portion 16 which is adapted to slide under the dog 70 and project its engaging portion through the hole as described. This actuating member is in the structure illustrated formed of a piece of wire. An actuating lever 17 is provided for the actuating member, the lever 75 being pivoted within the axle at 18 provided with a projecting finger piece 19 for convenience in manipulation. The actuating member is provided with an eye 20 engaging the pin 21 on the lever—see Figs. II, III 80 and IV.

With the parts thus formed and arranged, they are economically produced and assembled. The wheels may be mounted without the aid of tools, so that the carriage can 85 be shipped in "knock-down" and set up by the retailer or consumer as the case may be.

I have illustrated and described my invention in an embodiment which I have found very satisfactory. I have not attempted to 90 illustrate certain modifications and adaptations which I contemplate, as I believe the disclosure made will enable those skilled in the art to which my invention relates, to embody or adapt the same as may be desired.

Having thus described my invention, what I claim as new and desire to secure by Letters Patent is:

1. In a wheel retaining means, the combination of a hollow axle having a hole at the outer end thereof, a wheel mounted on said axle, a bar-like retaining dog disposed in said axle and provided with a laterally projecting wheel engaging portion adapted 100 to be projected through said hole, said dog having an offset at its inner end engaging the axle so that the dog is normally supported in an outwardly inclined retracted position, and a rod-like actuating member dis- 105

posed in said axle to reciprocate at the side of said dog and having a lateral curved offset at its outer end adapted to engage said retaining dog so that when the actuating member is actuated it slidably engages said retaining dog and projects its engaging portion through said hole.

2. In a wheel retaining means, the combination of a hollow axle, a wheel mounted on said axle, a retaining dog mounted in said axle and provided with a wheel engaging portion adapted to be projected laterally from said axle, an actuating member

slidably disposed in said axle to slidably engage said dog to project the same, and a lever for actuating said actuating member mounted within said axle and provided with a finger piece projecting therefrom.

In witness whereof, I have hereunto set my hand and seal in the presence of two witnesses.

CHARLES A. LINDBERG. [L. S.]
